VEHICLE BODY MOLDING

Robert J. Scheelk, Oak Park, Mich., assignor to General Motors Corporation, Detroit, Mich., a corporation of Delaware

Application August 8, 1957, Serial No. 47,276

Term of patent 7 years

(Cl. D14—6)

Figure 1 is a side elevational view of a vehicle body molding according to my new design;

Figure 2 is a perspective view of the molding;

Figure 3 is a sectional view taken on the plane indicated by line 3—3 of Figure 1;

Figure 4 is a sectional view taken on the plane indicated by line 4—4 of Figure 1;

Figure 5 is a sectional view taken on the plane indicated by line 5—5 of Figure 1;

Figure 6 is a sectional view taken on the plane indicated by line 6—6 of Figure 1;

Figure 7 is an enlarged sectional view taken along the plane indicated by line 7—7 of Figure 2; and

Figure 8 is an enlarged perspective view of a portion of the upper molding strip of Figure 2.

The portions of the automobile shown by means of broken lines are disclosed for illustrative purposes only.

I claim:

The ornamental design for a vehicle body molding, substantially as shown and described.
